Attorney.

UNITED STATES PATENT OFFICE

WALTER R. BRANDAU, OF LOS ANGELES, CALIFORNIA

SIPHONIC AIR-LIFT TRAP

Application filed January 16, 1932. Serial No. 587,077.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to devices of the class commonly designated as "air-lifts," for pumping water or other liquids by means of compressed air, without employing mechanism or moving parts. Among its salient objects are: first, to provide a greatly improved device of this nature, that is adapted for higher lifts, and for use in deeper wells, than the types of air-lifts that hitherto have been employed; second, to provide an air-lift that is adapted for securing greater operating efficiency than has previously been possible; third, to secure, in such a device, a uniformly continuous discharge; and, fourth, to accomplish the above by means of relatively simple and inexpensive apparatus.

My objects are attained in the manner illustrated in the accompanying drawing, in which:—

Figure 1 is a sectional elevation of a well with my improved device therein, the apparatus being shown broken for convenience of illustration; and partly in elevation and partly in central section;

Figure 2 is a plan view of the well and of my apparatus therein; and

Figure 3 is a view of the bottom of the apparatus, as it would appear when looking upwardly thereto.

Similar reference numerals refer to similar parts throughout the several views.

In all air-lift pumping apparatus, utilization is made of the principle that a column of fluid that is partly mixed with air, is of less weight than a column of homogeneous liquid of similar height. The first devices of this nature were relatively crude, and consisted essentially of a compressed air nozzle directed upwardly in the lower end of the

discharge pipe, the latter being submerged in the well to be pumped. In such devices, the air discharged from the nozzle creates what are commonly termed "air pistons", spaced by short columns of liquid; and the whole composite mass of liquid and air moves upwardly within the discharge line by reason of the continuous formation of new air pistons, and the fact that the composite contents of the discharge line weigh less than a corresponding column of the homogeneous liquid that surrounds the discharge line on the outside. Such a device is effective to pump liquids, but obviously the discharge occurs as intermittent alternating quantities of liquid and air. The power required for operating such devices fluctuates rapidly, by reason of the intermittent nature of the discharge; and other operative difficulties are caused by this intermittent action.

Later devices attempt to overcome the above difficulties by commingling the liquid and air, in such manner that the discharge column will consist of liquid containing relatively small bubbles of air, uniformly dispersed through the mass.

I have discovered a method, and provided apparatus, for securing in the discharge column, liquid that is uniformly mixed with a vast number of very small air bubbles; so that, in effect, it resembles a froth. This results in an exceedingly uniform discharge that is free from pulsations, and that requires a uniform in-put of power.

One of the principal advantages of securing the above result will become apparent when attention is called to the well known fact that the efficiency graph of practically all prime movers, such as electric motors, is curvilinear; and this efficiency reaches its maximum at a point somewhere near the capacity of the power source. If, for instance, an electric motor is operated at any other load than that for which it is designed, its efficiency will be lower than its maximum efficiency. In the case of a motor employed for causing a pulsating discharge flow, the output of the motor necessarily will be pulsating, and its operating efficiency cannot be at the maximum throughout its operating cycle. By securing

a uniform discharge flow, which my apparatus is adapted for providing, a suitable prime mover may be employed in such manner as to operate continuously at its maximum efficiency.

Passing to a detailed description of my invention, I have illustrated a section of a deep well, lined with a casing 5. My apparatus is depicted in operative relation to this well, except that no attempt has been made to illustrate the homogeneous liquid in the well, or the composite fluid in the discharge line. To do this would be difficult, and it would result in confusing the drawing. It has therefore been thought better to refer to the following description, as to the action of the device in breaking up the liquid and commingling it with air. It will be understood that the apparatus is necessarily submerged when it is being operated.

At 6 I have shown the lower end of the discharge line from the apparatus. This line may be made up of pipe leading to the top of the well, and therefrom to the point where the discharge is to be delivered. The lower end of the discharge line is attached to the air-lift apparatus proper, by any suitable means, as by the screwed coupling 7.

My air-lift comprises an outer cylindrical shell 8, closed at the top by means of the dome fitting 9, which is screwed into coupling 7. A co-axial inner barrel 10, of the same diameter as the discharge line, extends downwardly within the outer shell to a point relatively near the bottom. A co-axial booster nozzle 11 extends upwardly into barrel 10 from the bottom of the device, through the spheroidal bottom of an intermediate cylinder 12. The diameter of this intermediate cylinder is considerably larger than that of the barrel 10, and is smaller than that of shell 8. It is open ended at the top, and is spaced and supported in co-axial relation to the inner barrel and outer shell by means of riveted studs 13, of which one is shown.

At the bottom of the device is a co-axial intake nozzle 14, extending upwardly into the shell for a small distance. This nozzle is surrounded by a compressed air chamber 15 of substantial volume; and the outer wall 16 of this chamber is so shaped, and cooperates with the wall of the intake nozzle in such a manner, as to form a narrow annular blast orifice at 17 surrounding the upper extremity of the intake nozzle.

A hollow annular fitting 18 conveniently encircles discharge line 6, and affords an annular chamber for receiving and distributing the compressed air used for pumping. Compressed air is supplied to this chamber by means of the air supply line 19, and is distributed therefrom by several downwardly leading air pipes connected to the chamber at the bottom, as by means of the unions 20. Thus, air pipe 21 leads to the booster nozzle 11;

and three other air pipes, designated 22, lead into the bottom of chamber 15 at points spaced approximately 120 degrees, as indicated in Fig. 3.

I prefer to employ ball valves at or near the outlets of each of the last mentioned air pipes, as indicated at 23 and 24; for the purpose of avoiding possible silting troubles when the device remains idle in the well for considerable periods. I have found that it is relatively easy to blow out such silt deposits as can occur above the valves, but that it is more difficult to dislodge silt when it accumulates in the necessary U-bends at the lower ends of the air pipes.

When the above described device has been lowered into a well, suspended from the lower extremity of discharge line 6, and submerged a sufficient depth below the liquid level of the well, compressed air is supplied through line 19 and distributed by means of fitting 18 to the smaller air pipes 21 and 22. Chamber 15 will thus be filled with compressed air that will be discharged therefrom upwardly through the annular orifice 17 at high velocity, as indicated by arrow 26. This will have the effect of drawing the liquid of the well into intake nozzle 14, as indicated by arrow 27. The air blast will surround the column of incoming liquid, and impinge upon it by reason of the converging directions of the respective flows. This will result in separating the liquid into small particles, and cause it to become a mixture of liquid and air. This mixture will impinge upon the spheroidal bottom of cylinder 12, with a tendency to further break up the bodies of liquid into smaller particles. The mixture of liquid and air will then pass upwardly through annular passage 28, impinge upon the inner surface of dome 9 at 29, and be reflected from the latter downwardly into annular passage 30, as indicated by arrow 31. At the bottom of this passage the mixture of air and liquid will again be reflected by the upper surface of the spheroidal bottom of cylinder 12, as indicated by arrow 32, and then pass upwardly into barrel 10 and the discharge line.

From this point the mixture of liquid and air would naturally rise in the discharge line, by reason of its being of less weight than the corresponding surrounding column of liquid in the well; providing the discharge head is not too great, and that the device has been sufficiently submerged. However, to secure a more rapid discharge, to provide means for discharge against a greater head, and to make a smaller submergence necessary, the booster nozzle 11 is provided. Compressed air discharged from this nozzle, as indicated by arrow 33, not only acts directly upon the column in the discharge line to move it upwardly by reason of the direct pressure exerted thereon, but it will have the effect of

further aerating the column in the discharge line to lessen its weight, and to further break up the mixture in the discharge line into very small particles of liquid interspersed with very small air bubbles.

It will be noted that air blasts from annular nozzle 17 and booster nozzle 11 impinge directly upon the liquid. It will be noted further that the mixture of liquid and

10 air impinges upon the reflecting surfaces of the bottom of cylinder 12, and dome 9. Still further, it will be seen that at the points indicated by arrows 31 and 32, the direction of the fluid is reversed; thereby creating great 15 turbulence. As a result of all these actions, the liquid becomes very finely divided, and interspersed with very small air bubbles, so that when it is discharged, it is in the nature of a froth that flows very uniformly and 20 without pulsations. Obviously, the power required for pumping such a mixture will be very uniform, and may be provided by a prime source of power operating at its maximum efficiency.

25 For purposes of illustration, the construction of the device has been simplified as far as possible but, nevertheless, a perfectly practical form of construction has been shown. The annular pressure chamber in fitting 18 30 may be made in casting the fitting, by coring. The dome 9 may be made as a casting, by swaging or by welding. The various shells may be assembled by screwing together as shown, or they may be riveted together. 35 The air chamber 15 may be built up of swaged or pressed material, welded together, and bosses 34 may be welded to the bottom thereof.

By providing a screw thread 35 at the lower 40 end of intake nozzle 14, it is possible to attach a tail pipe to the device for reaching the ultimate bottom of a well. In such case it will be necessary to remove the U-bend at the lower extremity of pipe 21, and to connect 45 up booster nozzle 11 with the air supply in some other manner. This can be done by leading air pipe 21 through the side of shell 8 and through the wall of intermediate cylinder 12. Ball valve 24, if it is desired to retain 50 it, should then be located within cylinder 12.

I sometimes find it desirable to make a number of small perforations 36 in the outer wall of air chamber 15, to further assist in 55 aerating the liquid. The advantage of employing these will depend upon various operating conditions; such as the submergence, the height of the lift, and the available air pressure for operating the device.

60 It will be understood that the length of the device, if properly designed, will be much greater than Fig. 1 would indicate. The inspiratory action of annular orifice 17 will also be fully understood by those familiar 65 with this art.

I desire to call particular attention to the fact that various succeeding steps in the functioning of my device, although primarily for the purpose of converting the incoming liquid into finely divided particles mixed 70 with minute air bubbles, will assist in moving the mixture and overcoming its frictional resistance. Thus the down-falling mixture in annular passage 30 will exert a siphonic effect capable of lifting practically the same 75 height of mixture in annular passage 28; and the inspiratory action of booster nozzle 11 will strongly aid in moving the mixture through the preceding passages of the device.

Having thus fully described my invention, 80 I claim:

1. A device of the character described, comprising; an intake nozzle; a surface above the inner end of said nozzle adapted to deflect a flow impinging thereagainst; a narrow 85 annular passage surrounding the inner end of said nozzle whereby an annular jet may be caused, to draw liquid into the device through said nozzle, and to impinge upon said liquid after it has been deflected by said 90 surface; and means for discharging the liquid from said device.

2. A device of the character described, comprising; a central intake nozzle at the bottom; a surface above the inner end of said 95 nozzle adapted to deflect outwardly and upwardly an upward flow of liquid impinging thereagainst; a narrow annular passage surrounding the inner end of said nozzle, adapted for forming an annular inspiratory 100 jet for causing liquid to be drawn into the device through said nozzle; and means for discharging the liquid from said device; the annular passage being so directed as to cause 105 the jet issuing therefrom to impinge upon said liquid after it has been deflected by said surface.

3. A device of the character described, comprising; a central intake nozzle at the bottom; a surface above the inner end of 110 said nozzle adapted to deflect outwardly and upwardly an upward flow of liquid impinging thereagainst; a pressure chamber surrounding the lower end of said nozzle; a narrow annular passage surrounding the inner end of said nozzle and communicating directly with said chamber; and means for discharging the liquid from said device; said 115 passage being adapted for forming an annular inspiratory jet for causing liquid to be 120 drawn into the device through said nozzle, and being so directed as to cause the jet issuing therefrom to impinge upon said liquid after it has been deflected by said surface.

4. A device of the character described, comprising; a central intake nozzle at the bottom; a spheroidal surface above the inner end of said nozzle adapted to deflect outwardly and upwardly an upward flow of 130

liquid impinging thereagainst; a pressure chamber of substantial volume surrounding the lower end of said nozzle; means for conducting compressed air into said chamber; 5 a narrow annular passage surrounding the inner extremity of said nozzle and communicating directly with said chamber; and means for discharging the liquid from said device; said passage being adapted for forming an 10 annular inspiratory air jet suited for causing liquid to be drawn into the device through said nozzle, and being so directed as to cause the jet issuing therefrom to impinge upon said liquid after it has been deflected by said 15 surface, and so as to break up the body of liquid and produce a mixture of liquid and air bubbles.

5. The construction set forth in claim 4, in combination with means for imparting an 20 additional velocity head to the mixture of liquid and air.

6. The construction set forth in claim 4, in combination with air-jet means for imparting an additional velocity head to the 25 mixture in said discharge line.

7. The construction set forth in claim 4, in combination with; means for causing said mixture to impinge upon deflecting surfaces, for reversing its flow direction, and for thereby creating turbulence for breaking up the mixture into still smaller particles of liquid and air; and air-jet means in the discharge line for adding additional air to the mixture while imparting an additional velocity head thereto.

8. The construction set forth in claim 4, in combination with; means for causing said mixture to impinge upon deflecting surfaces, for reversing its flow direction, and for thereby creating turbulence for breaking up the mixture into still smaller particles of liquid and air; intermediate siphonic means for assisting the movement of mixture through the passages of the device; and air-jet means 45 in the discharge line for adding additional air to the mixture while imparting an additional velocity head thereto.

9. A device of the character described, comprising; an outer cylindrical shell that is 50 closed at the top; a co-axial discharge line leading from a point in the interior of the shell near its bottom, and upwardly through its top; a co-axial open-top cylinder with a closed bottom within the shell, spaced from 55 the inner wall of the shell and the outer wall of the discharge line; air-jet means for drawing liquid into the bottom of the shell and thereafter forcing it consecutively upwardly and downwardly through the angular passages formed by said cylinder and said walls; and upwardly directed air-jet means within 60 the discharge line at the lower end thereof.

10. A device of the character described, comprising; an outer cylindrical shell that 65 is closed at the top; a co-axial discharge line

leading from a point in the interior of the shell near its bottom, and upwardly through its top; a co-axial open-top cylinder with a spheroidal closed bottom within the shell, spaced from the inner wall of the shell and the outer wall of the discharge line; a co-axial intake nozzle leading into the bottom of the shell and terminating short of said spheroidal bottom; an annular pressure chamber surrounding said intake nozzle near its bottom; a co-axial annular passage of narrow width surrounding the upper end of the intake nozzle and communicating with said chamber; and upwardly directed air-jet means within the discharge line at the lower end thereof.
